(57) **CLAIM**

The ornamental design for a portion of an X-ray apparatus for medical treatment, as shown and described.

DESCRIPTION

FIG. 1 is a front, top and left side perspective view of a portion of an X-ray apparatus for medical treatment, showing my new design;

FIG. 2 is a top plan view thereof;

FIG. 3 is a bottom plan view thereof;

FIG. 4 is a left side elevational view thereof;

FIG. 5 is a front elevational view thereof;

FIG. 6 is a right side elevational view thereof; and,

FIG. 7 is a rear elevational view thereof.

The broken lines in the drawings are included for the purpose of illustrating portions of the X-ray apparatus that form no part of the claimed design.
